US0D1067591S

(12) United States Design Patent (10) Patent No.: US D1,067,591 S
(45) Date of Patent: * Mar. 25, 2025

(54) SLIPPER

(71) Applicant: Putian Jiefan Trading Co., Ltd, Putian (CN)

(72) Inventor: Jie Qiu, Putian (CN)

(73) Assignee: Putian Jiefan Trading Co., Ltd, Putian (CN)

() Term: 15 Years

(21) Appl. No.: 29/946,853

(22) Filed: Jun. 12, 2024

(51) LOC (15) Cl. 02-04

(52) U.S. Cl.

USPC D2/919

(58) Field of Classification Search

USPC D2/896, 916, 917, 919, 923, 924, 925, D2/926, 927, 928, 929, 936, 939, 940, D2/943, 947, 951, 953, 954, 956, 957, D2/960, 969

(57) CLAIM

The ornamental design for a slipper, as shown and described.

DESCRIPTION

FIG. 1 is a front perspective view of a slipper, showing my new design;

FIG. 2 is a rear perspective view thereof;

FIG. 3 is a left side view thereof;

FIG. 4 is a right side view thereof;

FIG. 5 is a front view thereof;

FIG. 6 is a rear view thereof;

FIG. 7 is a top view thereof;

FIG. 8 is a bottom view thereof;

FIG. 9 is an enlarged detail view of area 9 in FIG. 1; and, FIG. 10 is an enlarged detail view of area 10 in FIG. 6.

The dash-dot-dash broken lines encircling the enlarged views are for annotative purposes only and form no part of the claim thereof.

1 Claim, 10 Drawing Sheets
